PRONGED WIRE PIN

Daniel I. Reiter, New York, N. Y.

Application September 30, 1947, Serial No. 776,912

20 Claims. (Cl. 24—152)

1

This invention relates to the pointed spurs of wire articles such as double pointed pins and the like, the pins being designed to fasten seat covers to the upholstery fabric of automobiles and the like.

In pins with single legs, a pointed spur has been provided heretofore at the free end of the wire forming the head of the pin to prevent the pin from working loose from the seat cover. While heads of various kinds may be formed intermediate the pointed ends of a double pointed pin, no free wire end can be provided in the head, from which end a spur might be formed. Consequently, such spurs have heretofore been made, not from the head of the pin, but from the sheet material of the cap with which the head is covered with consequent disadvantages, or else the spur has been completely omitted. Where the spur is on the cap, not only is additional material required but care must be taken to locate the spur between the legs of the pin accurately on assembly of the cap and pin at additional expenditure of time and labor and increased cost of manufacture.

The present invention therefore contemplates the provision of an elongated pointed spur at any point desired in a length of wire of any desired cross-sectional shape and of any desired outline, such as the head of a double pointed pin.

The invention further contemplates the provision of a generally pointed or edged spur, integral with and partly severed from the wire of which a double pointed pin is made, and suitably bent from the wire to project at the required angle to perform its function, whereby the spur may economically be formed at the proper point in the head itself of such pin, regardless of whether the head is to be later capped or not, and the cap if used, may nevertheless be easily secured to the head in the usual manner as if the spurs were not present.

The various objects of the invention will be clear from the description which follows and from the drawings, in which

Fig. 1 is a fragmentary rear elevational view of one form of a typical capped double pointed pin illustrated as made of square wire and showing a pair of spurs split or sheared from a portion of the substantially U-shaped head of the pin, the legs of the pin being partly broken away to show the underlying head.

Fig. 2 is a vertical sectional view thereof.

Fig. 3 is a fragmentary view similar to Fig. 1 of another form of a typical capped double pointed pin made of round wire and showing a

2

single spur sheared and bent transversely from the substantially circular head.

Fig. 4 is a side elevational view of Fig. 3, the cap being omitted.

5 Fig. 5 is a fragmentary rear elevational view of another typical form of a capped double pointed pin, showing the spurs cut from flattened parts of the round wire of the head loop, part of one leg as well as the other leg and the part of the head adjacent thereto, being broken away to show the underlying parts.

Fig. 6 is a vertical sectional view, similar to Fig. 2, of the pin of Fig. 5.

10 Fig. 7 is an enlarged front elevational view of a portion of a length of round wire, having a flattened part from which the spur is sheared and bent.

Fig. 8 is a side elevational view of Fig. 7.

15 Fig. 9 is an enlarged side elevational view of a portion of a length of rectangular wire bent into partly circular form and having an integral spur cut therefrom.

Fig. 10 is a front elevational view of Fig. 9.

20 Fig. 11 is a front elevational view of a portion of a length of elliptical wire having a spur cut therefrom.

Fig. 12 is a side elevational view of Fig. 11.

25 In what follows, it will be understood that any of the pins of Figs. 1-6 may be made of wire of any desired cross-sectional shape such as square, round, rectangular, elliptical or the like, that the heads of any of the pins may take any desired form such as U-shaped with straight sides (Fig. 1), U-shaped with circular sides (Fig. 3) or inverted U-shaped with side bends so that the head is generally W-shaped (Fig. 5), that any desired number of spurs may be formed from any of the heads of the pins illustrated, such as one in Fig. 3 or two in Figs. 1 and 5, that the spurs may be severed from corresponding (Fig. 5) or non-corresponding (Fig. 1) portions of a symmetrical pin head, that the spurs may be of any desired length and shape and may be bent at any desired angle laterally or transversely to the general plane of the adjacent material or of the wire article, and that the terms "point" and "pointed" as used herein, are intended to refer to a sharp edge as well as to a point of a well known type such as a needle point.

30 35 40 45 50 55 55 In the form of the invention shown in Figs. 1 and 2, the wire of which the pin is made is illustrated, for the purpose of showing a practical embodiment of the invention, as of square cross-sectional shape, and the head 10 is illustrated as generally U-shaped, though as above indicated,

the head may be of any convenient shape and the wire of any cross-sectional shape instead of the square wire shown. The legs 11 and 12 of the pin terminate in suitable points 11' and 12' and the sheet metal cap 13 engages the bottom part of the head 10 as well as the bend at the upper ends of the legs, a projection as 14 being preferably interposed between the legs to hold the parts firmly in their proper positions.

One or more pointed spurs 15 and 16 are formed from the square wire of the head 10 by slicing, shearing or otherwise severing part of the wire material of the head incompletely away from the adjacent wire material and bending the severed part laterally out of the general plane of the head to arrange the resulting spur at the proper angle, in which it is directed toward the legs but extends in a general direction opposite to the direction of the legs, and is thereby enabled to perform its proper fabric-engaging function and to prevent retraction of the pin, once the legs have been inserted into the slip cover and upholstery to their full lengths.

The spur 15 is shown as severed from the inner edge of the head 10 while the spur 16 is severed from the outer edge of the head. It will be understood, however, that either spur may be cut from any edge part of the head as hereinbefore indicated, or from corresponding points as shown in Fig. 5. As shown, to form the spur 15, the spur material is severed from the head along a diagonal line or surface 17 beginning at the inner edge 18 of the head and extending across the face 19 of the head to a point as 17' approximately half way between the inner edge 18 and the outer edge 20. Hence the surface 17 of the spur is of the same size and shape as the wall 22 of the recess 21 in the head, resulting from the removal and bending of the spur material out of the plane of the head to the position shown in Fig. 2. The spur or spurs are preferably formed simultaneously with the bending thereof, after the length of wire from which the pin is made, has been bent or doubled to form the first bend 29 of the head and before the second bends 23 are made to double the legs back on the head 10.

The spur assumes a position in which it is bent about that end 34 thereof opposite its pointed end 33 and adjacent the end point 17' of the sheared surface 17, said end 34 remaining integrally attached to the wire.

While the spurs illustrated are shown for clarity slightly spaced laterally from the adjacent material from which they are severed, in practice the spurs are frequently not spread, but are intended to be aligned with the walls of the recess resulting from the shearing operation by which they are formed.

The pin shown in Figs. 3 and 4 is optionally made of round wire having a circular head 40 generally U-shaped but subtending an angle greater than 180°, legs 41 extending from the head and a cap 42. In the form shown, a single spur 43 is sheared from the wire of the head by the single straight but inclined cut 44, similar to the cut 17 and similarly made about half way across the thickness of the wire in one direction and completely through the wire in a perpendicular direction. The resulting spur 43 is bent away from the adjacent material toward one of the legs and into a position between the legs, and is directed slightly rearwardly, but extends in a general direction opposite to that of the legs. The spur point 45 is therefore in a position to perform its fabric-engaging function when the

pin is retracted after it has been pushed into its operative position through a slip cover and upholstery. The end 46 of the spur opposite its point remains integrally attached to the pin head as hereinbefore described in connection with Fig. 1. The cap 42 may obviously be set on and secured to the head in any rotated position, since the holding flange 47 thereof, though shown partly broken away to expose the second bends 48 of the head, is of uniform width throughout and symmetrical about all its center lines and no irregularities such as prongs or projections occur in the cap.

In that form of the invention shown in Figs. 5 and 6, as made of round wire, those parts 50 of the generally W-shaped head 51 from which the spurs 52 are to be cut, are flattened in the general shape shown in Figs. 7 and 8 on an enlarged scale, to increase the width thereof and thereby to facilitate the spur-forming operation. The cut, shearing the spur from the adjacent flattened material of the wire, may be straight throughout as shown by the cut surface 53 of Fig. 7, or may be a broken line as 54, 55 of Fig. 5, composed of two intersecting straight lines, or of any other suitable shape, as shown for example in Fig. 10. The flattening operation may be performed as the wire is at rest after the first bend 56 has been made therein and just prior to the spur formation. The spurs 52, as in the forms of the invention above described, extend toward the legs, but point in a direction opposite to that of the legs 57.

Figs. 7 and 8 show the spurs 58 partly severed from the flattened part 59 of a length 60 of round wire which has bends 61, 62 therein, the spur 58 being bent out of the plane of the flattened part 59 at the desired angle and being attached to said part integrally at one end 63 and pointed at the opposite free end 64.

In Figs. 9 and 10, the wire 66 illustrated is of rectangular cross section and is bent into circular form to show that wire of any suitable cross-sectional shape, bent in any manner, may have an integral projecting pointed spur sheared therefrom according to this invention. The spur-forming cut consists of the inclined straight cut 67 forming the point 68 at one end of the spur 69, and the meeting arcuate cut 70 arranged concentrically with and approximately half way between the side edges of the wire. The other end 71 of the spur is integrally joined to the wire and supported thereby. While the spur in this case is shown as curved in one direction, it will be understood that it may be straightened during the spur-bending operation.

In Figs. 11 and 12, the portion 73 of a length of wire of elliptical cross section is provided with the pointed spur 74 sheared from the portion 73 by a pair of intersecting cuts as 75, 76. The part from which the spur is severed, may first be further flattened if desired, in the same manner as shown and described in connection with Fig. 7, and the spur may be formed at a curved portion of the wire if desired, as shown in Fig. 10. In any case, the spur is integrally connected with the wire at one end, pointed at the other end, and bent out of the general plane of the wire.

It will therefore be seen that I have provided a pointed straight or curved projecting integral spur at any part of a length of wire of any cross-sectional and peripheral shape, that the spur may be directed inexpensively at a proper angle to the general plane of the remainder of the wire to provide a point at one end spaced from the

wire, while the other end remains attached integrally to the wire, that such spur is well adapted for formation at the head of a double pointed capped or uncapped pin wherein no integral spur has previously been available, that the spur may be formed as an intermediate step in the formation of the pin, and that the invention is well adapted for its intended purposes of producing a point for easily piercing or entering fabric or other suitable material on manipulation of the pin or other article from which it projects.

While I have shown and described certain specific forms of the invention, numerous other forms along the lines of those disclosed herein, will now be obvious, and other changes may be made herein without departing from the spirit of the invention as defined in the appended claims.

I claim:

1. A double pointed pin of a length of round wire comprising a pair of substantially parallel straight cylindrical legs, each leg having a point at the free end thereof, a bend at the other end of each leg, a head extending from the bends and joining the legs and having two straight parts therein each joined by a bend to the other straight parts, the bends and legs being of part of the length of round wire, a straight part being flat for substantially the distance between bends, and a pointed spur extending from the material of and integral at one end with the remainder of the straight part and arranged at an acute angle thereto and extending laterally of the head to a point adjacent to and between the legs, there being a recess in the edge of the straight flat part of the head resulting from the arrangement of the spur, the spur being of the material initially at the extreme edge portion of the straight part.

2. A double pointed pin of a single piece of wire comprising a pair of transversely spaced apart coextensive legs each pointed at its free end, the free ends of the respective legs being arranged at the same end of the pin, a first bend at the other end of one leg, a similar second bend at the other end of the other leg, the respective bends extending in the same direction laterally of the legs, a head of that portion of the piece of wire intermediate the legs extending integrally from and between the bends and arranged generally in a plane in lateral spaced relation to the plane of the legs, said head including a third bend, and a spur integral at its base with the material of the head and extending laterally from said base toward the legs and longitudinally toward the first and second bends.

3. The pin of claim 2, the head being U-shaped.

4. The pin of claim 2, the head being circular.

5. The pin of claim 2, the head being in the form of a W.

6. The pin of claim 2, and a cap for the head embracing the third bend.

7. The pin of claim 2, the third bend subtending an angle of approximately 180°.

8. The pin of claim 2, the head having a pair of straight portions, one arranged between the first and third bends and the other arranged between the second and third bends, the spur extending from one of the straight portions.

9. The pin of claim 2, the third bend being arranged between and connecting the first and second bends and the spur extending from said third bend.

10. The pin of claim 2, the head comprising an

inverted U-shaped portion included the third bend, a fourth bend at one end of the inverted U-shaped portion, a similar fifth bend at the other end of the inverted U-shaped portion, a first straight part joining the first and fourth bends and a second straight part joining the second and fifth bends.

11. The pin of claim 10, part of the inverted U-shaped portion being flattened and the spur extending from said flattened part.

12. The pin of claim 10, and a cap embracing the third, fourth and fifth bends and normally concealing the head.

13. A double pointed wire pin of a single piece of wire comprising a pair of transversely spaced apart and substantially parallel similar legs arranged in side by side relation and each terminating in a point at the free end thereof and being otherwise straight and of uniform cross section and free of deformation, the points of the legs being at the same end of the pin and at opposite ends of the piece of wire, a head of the intermediate part of the piece of wire joining the other ends of the legs and arranged at the end of the pin opposite the points, said head having a bend therein adapted to engage the rim flange of a cap and arranged in a plane in lateral spaced relation to the plane of the legs, the head extending from said other ends of the legs toward the points, and a pointed spur extending angularly from the head and laterally toward the legs and integrally joined at one end to the head and reducing the width of the wire of the head at that part thereof adjacent the spur by approximately half the width of the wire.

14. The pin of claim 13, the spur extending from the head in a general direction opposite to the direction in which the legs extend.

15. The pin of claim 13, the head having a pair of substantially parallel sides extending from the respective ends of the bend and substantially parallel to the legs, and the spur extending integrally from one of the parallel sides toward said other ends of the legs.

16. The pin of claim 13, the bend subtending an angle greater than 180° and the spur being arranged at the mid-part of the bend between the legs.

17. A double pointed pin of one piece of wire comprising a first straight leg terminating in a point and arranged at one end portion of the piece of wire, a second straight leg terminating in a point and arranged at the other end portion of the piece of wire in substantially parallel and corresponding side by side transversely spaced relation to the first leg, a pin head of substantially the remaining intermediate portion of the pin integrally connecting the ends of the respective legs opposite the points thereof, said head having a central generally U-shaped portion arranged in a plane substantially parallel and in lateral spaced relation to the plane passing through the axes of the legs, and a bend at each end of the U-shaped portion and joining said U-shaped portion to the end portion of the adjacent leg opposite the point

thereof, the U-shaped portion of the head having a longitudinally extending recess in an edge part thereof, and a relatively rigid spur projecting laterally and angularly from the U-shaped portion toward the legs, the inner edge of the spur being in substantial alignment and co-planar with the walls of the recess, the spur having a point at one end thereof in lateral spaced relation to one end of the recess and at its other end being integrally joined to said edge part at

the other end of the recess and being approximately half the width of the wire.

18. The pin of claim 17, the head having a flattened part in the edge part of which the recess is provided, the flattened part being in a plane parallel to and in lateral spaced relation to the plane passing through the legs.

19. A double pointed wire pin of one piece of wire, comprising a first leg having a free pointed end and a laterally extending bend at the other end thereof, a second similar pointed leg coextensive with and spaced transversely from the first leg and having a laterally extending bend, a U-shaped head of the wire intermediate the legs joining the bends and arranged in a plane in lateral spaced relation to the plane passing through the legs and a spur extending from the head in a direction opposite the direction in which the legs extend and also extending toward the bends.

20. The pin of claim 19 and a cap having a flange embracing part of the head and parts of the bends.
